P. WEBER,
PHONOGRAPH HORN.
APPLICATION FILED MAR. 31, 1908.

Patented Nov. 28, 1911.

UNITED STATES PATENT OFFICE.

PETER WEEER, OF ORANGE, NEW JERSEY, ASSIGNOR, BY MESNE ASSIGNMENTS, TO THOMAS A. EDISON, INCORPORATED, OF WEST ORANGE, NEW JERSEY, A CORPORATION OF NEW JERSEY.

PHONOGRAPH-HORN.

1,010,333.

Specification of Letters Patent. Patented Nov. 28, 1911.

Application filed March 31, 1908. Serial No. 424,329.

To all whom it may concern:

Be it known that I, PETER WEBER, a citizen of the United States, and a resident of Orange, in the county of Essex and State of New Jersey, have invented certain new and useful Improvements in Phonograph-Horns, of which the following is a description.

My invention relates to phonograph horns of the type in which the flaring bell is made in a single piece which is separately united to the small end or body portion of the horn, and has been preferably embodied in a horn, the axis of which is curved so that the horn extends upward from the phonograph sound box and the mouth of the bell occupies substantially a vertical plane facing in the same direction as the phonograph, as described and claimed in my application filed October 14, 1907, No. 397,283.

20 The present invention also relates to improved means for flexibly uniting a horn of this character with the sound box of the phonograph.

In order that the invention may be more 25 fully understood, reference is hereby made to the accompanying drawing of which—

Figure 1 is a side elevation of a horn constructed in accordance with my invention and applied to a phonograph which is illustrated in dotted lines; Fig. 2 is a section on line 2—2 of Fig. 1; Fig. 3 is a detail plan view of the means for locking the bell to the body of the horn; Fig. 4 is a section on line 4—4 of Fig. 3; Figs. 5 and 6 are views 30 similar to 3 and 4 of a modified locking device; Figs. 7 and 8 are similar views of another modification; and Fig. 9 is a view similar to the lower portion of Fig. 1, showing a phonograph in which the nipple of the 35 sound box extends vertically and showing a modified construction of coupling for connecting the lower end of the horn with the said nipple.

The horn shown comprises a bell 1 of 40 metal, wood or other suitable material, the small end of which is provided with a pair of apertures 2 and an outwardly extending pin 3. 4 is a curved section or body, the small end of which is adapted to be connected to the sound box of the phonograph *a*. The large end of the section 4 is provided with a metallic ring 5 of tapered form which has a pair of inwardly projecting pins 6 adapted to be inserted within the 45 openings 2, and said ring is formed with a

notch 7 adapted to receive the pin 3. There is a locking latch 8 pivoted at 9 to the ring 5, the same being formed with a handle 10 and a cam surface 11, which tends to draw the bell 1 into the ring 5 with a wedging action, due to the tapered form of these parts. 80

In the device of Figs. 5 and 6 there is a locking latch 8' pivoted at 9' to the lugs 12 which are rigid with the ring 5. The forward end of said latch 8' is provided with a handle 10' and the latch has an opening 11' which is adapted to receive the pin 3, and there is the same wedging action of the bell 1 with respect to the ring 5 as the parts 70 are drawn together by the latch 8' being forced down upon the pin 3 into the position shown in Fig. 6.

In the device of Figs. 7 and 8, the latch 8' which is pivoted at 9' to the lugs 12 carried by the ring 5, is formed with a handle 10' and a cross-rod 11', which co-operates with a yoke or Y-shaped member 13 secured to the bell 1, to wedge the bell within the ring 5, the surface of the yoke 13 having a 75 cam action with respect to the cross rod 11'. 80

The small end of the section 4 may be united to the nipple *b* of the sound box by any suitable flexible connection, but I prefer to use a hollow or tubular ball and socket joint or coupling 14. In the structure shown in Fig. 1, this coupling fits tightly upon the nipple *b* and slides freely within the lower end of the section 4. 85

In the structure shown in Fig. 9 the phonograph carriage *a'* is of slightly different form, and the nipple *b'* of the sound box extends vertically. With a phonograph of this type, one member of the ball and socket coupling 14 may be integral with the section 4 as shown, and the other member fits loosely upon the said nipple *b'*. In both forms the weight of the horn is carried by a fixed support *c* from which the horn is suspended and the sliding connection between the horn 100 and coupling in Fig. 1 and between the coupling and nipple in Fig. 9, permits the progressive movement or feed of the phonograph carriage without affecting the connection of the sound box with the horn. 95

Having now described my invention, what I claim is:

1. A phonograph horn comprising separable sections at least one of which has a tapered engaging surface, and means for

- uniting the same comprising one or more pins carried by the end of one section and adapted to be inserted in openings formed in the other section, a pivotal latch carried by one section and adapted to engage a projection carried by the other section, said latch and projection being so formed that their engagement draws the sections together with a wedging action, substantially as set forth.
2. A phonograph horn comprising a pair of separable sections at least one of which has a tapered engaging surface, and locking means therefor comprising a latch pivoted to one of said sections, and a pin rigid with the other section, said latch being formed with a cam surface for engaging said pin and drawing said sections together with a wedging action, substantially as set forth.
3. A phonograph horn comprising a pair of separable sections, a stiffening ring applied to the end of one of said sections, a projection rigid with the other section, and a latch pivoted to said ring and adapted to engage said projection for drawing said section and ring together, said latch and pro-

jection being so formed as to exert a wedge-like or cam action on each other during the pivotal movement of the latch substantially as set forth.

4. A phonograph horn comprising a pair of separable sections, a stiffening ring applied to the end of one of said sections and provided with pins and with a notch, the end of the other of said sections being provided with openings adapted to receive said pins and with a projection rigid therewith adapted to be received by said notch, and a latch pivoted to said ring and adapted to engage said projection for drawing said pin into said notch and thereby drawing said section and ring together, said latch and projection being so formed as to exert a wedge-like or cam action on each other during the pivotal movement of the latch, substantially as set forth.

This specification signed and witnessed this 30 day of March, 1908.

PETER WEBER.
